UNITED STATES PATENT OFFICE.

THOMAS E. COLLINS, OF CHICAGO, ILLINOIS.

DOOR CHECK AND CLOSER.

1,353,219.

Specification of Letters Patent. Patented Sept. 21, 1920.

Application filed December 22, 1919. Serial No. 346,726.

To all whom it may concern:

Be it known that I, THOMAS E. COLLINS, a citizen of the United States, residing at Chicago, in the county of Cook and State 5 of Illinois, have invented certain new and useful Improvements in Door Checks and Closers, of which the following is a specification.

My invention relates to non-liquid door 10 checks and closers, the object being to provide a simple and efficient non-liquid device of this class with few parts in which the disadvantages inherent in the use of liquid are eliminated. A further object is to provide a device of this class which can be used 15 on right or left hand doors without any change or modification whatever. A further object is to provide a non-liquid device of this class which positively and gradually 20 returns the door to a closed position without slamming. A further object is to provide a device of this class with a brake for regulating the closing speed of the door. A further object is to provide a non-liquid 25 check and closer which prevents slamming and brings the door to an easy, even, gradual stop when opening. A further object is to provide an adjustable device of this class with resilient means for holding the 30 door in open and closed position.

Figure 1 is a plan view of a door check and closer, embodying one form of my invention, showing it applied.

Fig. 2 is an enlarged sectional view taken 35 on the line 2—2 of Fig. 1.

Fig. 3 is an enlarged sectional view taken on the line 3—3 of Fig. 2.

Fig. 4 is a detailed view of certain of the parts more fully described hereinafter.

Fig. 5 is a sectional view of the arms at 40 the point of connecting, as shown when in open position.

Referring to the drawings in detail. The door or swinging member shown in broken 45 lines, is indicated by the numeral (10) and is mounted by means of a hinge (11) on the frame (12).

The construction shown consists generally of a casing having ears or lugs by 50 means of which the casing is adapted to be mounted on a swinging member, like a door or window, in which casing is mounted a shaft provided with a spring motor adapted to operate the shaft in one direction,

which shaft is operatively connected by toggle arms to a bracket mounted on a frame adjacent the swinging member. 55

The casing indicated as a whole by the reference character (13), is preferably made or cast in two parts (14) and (15) which parts are connected together by means of a circular band or shell (16) and held in place by means of screws or bolts shown. Mounted in alined bearings in the casing is a driven shaft (17) which shaft on one end 60 extends outwardly beyond the casing. Mounted on the outwardly extending end of said shaft is a small gear wheel (18). Pivotaly mounted on the same side of the casing by means of a bolt (19) is a segmental rack (20) provided with internal gear teeth designed to mesh with the gear (18). Screwed to the rack (20) or rather formed integral therewith, is an arm (21) which arm at its outer end, is pivotally connected 65 to an extensible arm (22). The arm (22), at its inner end, is pivotally connected to a bracket (23), which bracket is screwed to the door frame by means of the screws shown. Mounted within the casing and surrounding the driven shaft (17) is a spring motor (24), which motor consists of a coil spring, the inner end of which, being attached to the collar (25), fixed to the shaft (17) and its opposite end to the anchor lug 70 (26). Adjacent to the motor and rotatably mounted on the shaft (17) is an automatically operated, centrifugally expanding 75 brake. This brake comprises a link (27) loosely mounted on the driven shaft (17) 80 to each end of which link, there is pivotally connected a swinging shoe (28). Fixed to each shoe is a weighted arm (29). Each shoe is provided with a frictionally engaging surface (30), preferably of leather, 85 Surrounding the perimeter of the brake 90 shoes, on the inside of the casing, is a brake drum (31), preferably of leather. Mounted in the casing by means of a spindle shaft (32) is a double-faced gear (33), one of 95 which faces is designed to mesh with a small gear (34), formed integrally with the hub of the link (27), while the other face (33) is designed to mesh with the large gear, (35), which is also loosely mounted on the 100 driven shaft (17) but operatively connected thereto when turning in one direction by 105 means of a pawl and ratchet. The ratchet

(36) fixed to the driven shaft (17) and rotatable therewith is designed to rotate the gear (35) by means of the spring pressed pawl (37). When the shaft is rotated in one direction, in the particular arrangement shown in Fig. 4 this action would take place when rotating in the direction indicated by the arrow.

As shown in Fig. 5, the arms (21) and (22) are, at their pivotally connected points, provided with means for resiliently holding the door in open position. In the embodiment shown, the arm (21) is provided with a groove having beveled sides and the arm (22) is provided with a lug having beveled sides, designed to register with the groove when the door has reached its open limit of movement. These members are resiliently held together by means of a coiled spring (38) surrounding the bolt (39) and held in place by the nut (40) so that when the door has reached its open limit of movement the coil spring snaps the lug into the groove and there holds it resiliently but only sufficiently to give when a slight force is exerted on the door.

Assuming the parts assembled as shown in the drawings, the operation is as follows: The door or swinging member, of course is opened in the usual manner, and while being opened, by means of the arms (21) and (22) and rack (20) and gear (18), the shaft (17) is caused to rotate, thus winding the spring motor (24) and storing up power therein. When the swinging member has reached its limit of movement, it is resiliently held in this position by means of the arms (22) and (21) and their connection. When it is desired to close the door, the operator gives a slight pull on the door to which the resilient connecting means of the arms (21) and (22) respond. The door then starts on its closing movement. The moment this starts the ratchet (36) engages the spring pressed pawl (37) on the gear (35) which gear in turn meshes with one of the faces on the gear (33). The other face of the gear (33) meshes with the gear (34) which rotates the link (27). As the link (27) rotates, the weights (29), are by centrifugal force, thrown outwardly causing the brake shoes (30) to frictionally engage with the brake band (31) and thus produce a gradual regulated closing, for as the speed of the shaft (17) increases, the frictional engagement of the brake shoes against the brake drum will be proportionally increased. The closing speed of the shaft (17) can also be regulated by increasing or decreasing the tension on the spring motor.

It will be obvious from the foregoing drawings and description that I have produced a door check and closer which is inexpensive to manufacture; which has extreme simplicity of parts; which has no oil

to leak out or evaporate, impairing the operation of the device; which has no packing or parts to wear out; which has no back pressure from oil passing through small hole when door is being opened, and making it hard to open; which needs no adjustment after being installed; which needs no changes whatever to be used on either right or left hand doors; which has the same speed at all points when door is closing.

Having described my invention, what I claim is:

1. In a door check and closer, the combination of a casing, comprising an upper and lower portion spaced apart, a driving shaft rotatably mounted in said portions, a brake band bridging said space and connecting said portions in a manner to provide an annular ring between said portions, a lining secured to said band within said annular ring, a frictional brake mounted on said shaft and designed to engage said lining on a predetermined movement of said shaft and a motor for rotating said shaft.

2. In a door check and closer, a casing, a driven shaft, rotatably mounted in said casing, a gear mounted on said shaft outside of said casing, a lever fulcrumed on said casing, a segmental gear, rigidly fixed to said fulcrumed lever, intermediate its ends and adapted to mesh with and revolve about said first mentioned gear and means for connecting said fulcrum lever to a door frame or the like, substantially as and for the purpose set forth.

3. In a door check and closer, a casing, a driven shaft rotatably mounted within said casing, a gear mounted on said shaft outside of the casing, a lever fulcrumed on said casing, a segmental gear fixed to said fulcrumed lever intermediate its ends, and adapted to mesh with and revolve about said first mentioned gear, a link adapted to connect said fulcrumed lever to a door frame or the like, a spring motor for operating said shaft in one direction and means designed to automatically retard the speed of said shaft when rotated by the motor.

4. In a door check and closer, the combination of a casing, a shaft rotatably mounted therein, a spring motor mounted on said shaft near one side of the casing for operating said shaft, a link loosely mounted on said shaft adjacent to the spring motor, frictional expanding brakes pivotally connected to said link and adapted to engage said casing adjacent to the spring motor, a small gear formed integral with said link, a second gear loosely mounted on said shaft adjacent to said small gear, a ratchet gear fixed to said shaft adjacent to said second mounted gear and means for operatively connecting said gears on a predetermined movement of said shaft, a stub shaft rigidly mounted in the opposite side

of said casing and a double faced gear rotatably mounted on said stub shaft substantially as and for the purpose set forth.

5. In a door check and closer, the combination of a casing consisting of upper and lower cylindrical portions, a brake band for connecting said portions, a shaft rotatably mounted in the sides of said casing, a spring motor mounted on said shaft in the upper 10 portion of said casing, a link rotatably mounted on said shaft adjacent to the spring motor and provided with pivotally mounted brake shoes for engaging said brake band, a small gear formed on the hub of said 15 link, a gear loosely mounted on said shaft adjacent thereto, a ratchet gear fixed to said shaft adjacent to said last named gear means for operatively connecting said gears on a predetermined movement of said shaft, 20 a stub shaft rigidly mounted in the lower portion of said casing, and a double faced

gear loosely mounted on said stub shaft substantially as and for the purpose set forth.

6. In a door check and closer, the combination of a casing, comprising an upper 25 and lower portion spaced apart, a driving shaft rotatably mounted in said portions, a readily removed band bridging said space and connecting said portions, a frictional brake mounted on said shaft and designed 30 to coöperate with said band for retarding the movement of said shaft on a pre-determined movement thereof and a motor for rotating said shaft.

In witness whereof, I hereunto subscribe 35 my name to this specification in the presence of two witnesses:

THOMAS E. COLLINS.
